DESIGN FOR A COLLAPSIBLE AUTOMOBILE CABIN

William N. de Sherbinin, Hastings on Hudson,
N. Y.

Application September 7, 1935, Serial No. 58,470

Term of patent 14 years

To all whom it may concern:

Be it known that I, William N. de Sherbinin, a subject of the King of Great Britain, residing in Hastings on Hudson, Westchester county, New York, have invented a new, original, and ornamental Design for a Collapsible Automobile Cabin, of which the following is a specification, reference being had to the accompanying drawings, forming part thereof.

In the drawings:

Fig. 1 is a right front perspective view of the collapsible automobile cabin embodying my new design;

Fig. 2 is a left front perspective view;

Fig. 3 is a right rear perspective view; and

Fig. 4 is a left front perspective view of the cabin after having been collapsed and folded into the form of a trunk.

The dot and dash lines in Figs. 1, 2 and 4 indicate the rear portion of an automobile upon which the cabin is mounted.

I claim:

The ornamental design for a collapsible automobile cabin, substantially as shown and described.

WILLIAM N. DE SHERBININ,
